LOOP PRONG BUCKLE

Application filed August 10, 1932. Serial No. 628,193.

This invention relates to improvements in loop prong buckles.

Loop prong buckles, previous to the improvement about to be disclosed, have been made and used in a manner common to all as regards the loop portion of such buckles, the loop portion being formed to provide a button-receiving loop, of sufficient interior dimensions to permit a button to be passed therethrough, and a button-retaining loop for the repose of the metal shank of an inserted button, these loops being defined by means of an intermediate contracted throat portion of sufficient width to admit button shanks of extreme diameter in passing from one loop to the other. The ease with which button shanks are able to leave the button-retaining loop of this type of loop prong buckle renders the button capable of unintentional release from the device when the strap thereby held is not taut. The improved loop prong buckle gives security to the retention of an inserted button and also eliminates the larger of the usual associated loops and also the contracted throat portion of the ordinary loop prong buckle. As regards the button-retaining loop portion of the improved loop prong buckle, there is similarity thereof with the button-retaining loop portions illustrated and described by your petitioner in the two applications filed by him on June 13, 1932 and July 25, 1932, Serial Numbers 616,868 and 624,375, respectively, the first of said applications disclosing such loop portion in connection with a loop slide buckle, and the second of said applications associating such loop portion with a rigid button loop, each of said applications including structure peculiar to other features including the cooperation of a folded strap portion to secure a seated button.

The object of the present improvement is to provide a prong buckle with a button-retaining loop portion so associated with a portion of a strap, an end of which is threaded into and held within the prong buckle, that the strap is adapted to cooperate with the retaining loop in preventing an unintentional release of a button inserted in the loop. With this and other objects as may hereinafter ap-

pear the invention is subject to such modifications as may come within the scope of what is hereinafter claimed.

The character of the improvement may be best understood by reference to one illustrative device embodying the invention and illustrated by the accompanying drawing in which the Figure 1 is an upright front elevation of the device having a seated button, a part obscured by the button being illustrated by dotted lines; the Figure 2 is a similar elevation of the device, but illustrating a button lifted from its seated position; the Figure 3 is an upright front elevation of the device as illustrated by the first figure, but having a strap end threaded into and held therein; the Figure 4 is an upright front elevation of the device as illustrated by the second figure, but having a strap end threaded into and held therein; the Figure 5 is a cross-section on the line 5—5 of the third figure, but illustrating the button attached to a member thereby supported; the Figure 6 is a cross-section on the line 6—6 of the fourth figure, but illustrating the button attached to a member thereby supported; and the Figure 7 is a cross-section similar to that of the next previous figure excepting that the button is illustrated in a tipped position and displacing a flexible portion of a strap.

Referring more particularly to the drawing the device, as illustrated, comprises the buckle frame 1, the pronged member 2 having the prongs 3 and 4, and the spaced pivotal connections 5 and 6 common to such buckles, the structure thereby including the relatively movable buckle loops 7 and 8 together providing the device with the upper bar 9 and the lower bar 10. The button-retaining loop 11 is formed in the lower bar 10, the base of the retaining loop 11 providing the seat 12 for the metal shank 13 of a button 14, the button 14 reposing in the seat 12 being illustrated by the Figures 1, 3 and 5. For the purpose of describing certain positions of the button 14 it is illustrated with a dotted horizontal diameter 20 and a dotted vertical diameter 21. When the shank 13 of a button 14 is seated within the retaining loop 11, as illustrated by the Figure 1,

the dotted horizontal diameter 20 lies below the lower bar 10, but when the button is raised inadvertently or otherwise, as illustrated by the Figure 2, the dotted horizontal diameter 20 lies above the lower bar 10, and in both instances the dotted vertical diameter 21 is intersected by the dotted straight line 22 connecting the lowest portions of said spaced pivotal connections 5 and 6.

10 A strap 30 is threaded into the device by inserting the end 31 of the strap 30 into the buckle loop 7 from the rear of the device, the prongs 3 and 4 being urged through the strap material as a positive holding means.

15 The end 31 of the strap 30 is then inserted into the buckle loop 8 from the front and pulled taut. In thus threading the strap 30 into the device, that portion 32 of the strap 30, lying over the spaced pivotal connections 5 and 6 and from thence dipping into the buckle loop 8, extends along the straight dotted line 22 but, because of the open space 23 between the spaced pivotal connections 5 and 6, a middle portion 33 of the strap 30 along said dotted line 22 remains flexible, it having no immediate support from a structural part.

20 In use, therefore, while, with no strap threaded into the device, there is ample space to insert a button 14 into the retaining loop 11 by way of the open space 23 yet, when the strap 30 is threaded into the device as aforesaid, the button 14 may be inserted and released only by the flexible yielding of the strap portion 33. To insert the button 14 into the retaining loop 11, the button 14 is tipped so that the rear surface 15 of the lower portion of the button 14 may engage the outer surface of the upper portion of the retaining loop 11, then by using that engagement as a fulcrum the top portion of the button may be urged past the yielding flexible portion 33 of the strap 30 and thus permit the button 14 to slide into the retaining loop 11 and the shank 13 to be seated upon the seat 12, as illustrated by the Figures 1, 3 and 5.

25 While thus inserted into the retaining loop 11, the button 14 is therein secured against unintentional release by reason of the fact that any casual movement of the button 14 within the retaining loop 11 is met by the strap portion 33 intersecting the vertical diameter 21 behind the button 14, that position of an unseated button 14 being illustrated by the Figures 2, 4, and 6. To release the button 14 from within the retaining loop 11, the button 14 is raised and inclined backwardly so that its horizontal diameter 20 is thereby raised above the lower bar 10, the top of the button 14 engaging and displacing the flexible portion 33 of the strap 30 thus yielding, as illustrated by the Figure 7, to permit the release of the button 14 from within the retaining loop 11.

I claim:—

1. A loop prong buckle comprising a buckle frame and a pronged member having spaced pivotal connections, one with the other, providing a space between the pronged ends of the pronged member, the frame and the member together providing upper and lower associated buckle loops, the pronged member having a button loop portion providing a seat for the shank of a button, the said portion being so formed that a button is insertable within and releasable from said button loop portion only through said lower buckle loop, and a strap threaded from the rear into said upper buckle loop and back into the lower buckle loop and thus maintaining a flexible strap portion extending across said space along a line intersecting the diameter of a button entering or leaving the button loop portion. 70

2. A loop prong buckle comprising a buckle frame loop and a pronged member loop having spaced pivotal connections, one with the other, providing a space between the pronged ends of the pronged member, the frame and the member providing upper and lower buckle loops, the lower buckle loop having a button-retaining loop portion providing a seat for the shank of a button, and a strap threaded from the rear into the frame loop and then back into the pronged member loop and thus providing a flexible strap portion extending across said space and lying in a substantially vertical plane parallel to and at the rear of the plane of a seated button, 90 said strap cooperating with the retaining loop to secure said button against unintentional release, but flexibly yielding to permit the forced tipping release and insertion of said button. 95
